UNITED STATES PATENT OFFICE.

DANIEL C. PETRIE, OF BILOXI, MISSISSIPPI.

FENCE-POST.

No. 848,921.

Specification of Letters Patent.

Patented April 2, 1907.

Application filed August 4, 1905. Serial No. 272,670.

To all whom it may concern:

Be it known that I, DANIEL C. PETRIE, a citizen of the United States, residing at Biloxi, in the county of Harrison, State of Mississippi, have invented certain new and useful Improvements in Fence-Posts; and I do hereby declare the following to be a full, clear, and exact description of the invention, such as will enable others skilled in the art 10 to which it appertains to make and use the same.

This invention relates to fence-posts, and has for its object to provide a novel form of artificial post which is produced by a molding process and is formed to enable the convenient connection therewith of picket fencing and wire fencing.

It is, furthermore, designed to have the post complete in itself in marketable form 20 and capable of being planted or set up in the manner of any ordinary fence-post.

With these and other objects in view the present invention consists in the combination and arrangement of parts, as will be 25 hereinafter more fully described, shown in the accompanying drawings, and particularly pointed out in the appended claim, it being understood that changes in the form, proportion, size, and minor details may be 30 made within the scope of the claim without departing from the spirit or sacrificing any of the advantages of the invention.

In the accompanying drawings, Figure 1 is a side elevation of a post embodying the 35 present invention. Fig. 2 is a transverse horizontal section. Fig. 3 is a sectional view.

Like characters of reference indicate corresponding parts in each of the several figures of the drawings.

40 The body of the present post is of any common or preferred shape and molded in any desired manner from plastic or liquid cement or other artificial material which is fireproof and capable of withstanding frosts 45 and the general effects of the weather.

By preference the post is substantially rectangular in cross-section, and adjacent each upright corner there is a stiffening element 2 molded therein and preferably consisting of one or more barbed wires, the barbs serving to anchor the wires in the post and prevent looseness thereof, while the wires serve to stiffen the post, tend to prevent cracking thereof, and also serve to hold the 55 posts together, even though it should become cracked entirely through.

In one face of the post a longitudinal dovetailed groove or channel 3 is formed during the molding of the post, said groove or channel being open at its upper end for the reception of a dovetailed wooden strip 4, which is fitted in the groove and after the post has been moved from the mold. The dovetailed shape of the groove serves to prevent lateral displacement of the strip and at the same 65 time exposes only a comparatively narrow portion thereof for the reception of staples 5 or other suitable fastenings (shown in the drawings) for connecting the runner-wires 6 to the post without damage to the body 70 thereof. It is of course apparent that the wire fencing may be formed of plain wires, barbed wires, or a wire fabric, and the fencing may be readily connected to the post merely by driving the fastenings into the wooden strip. 75 It will here be explained that it is proposed to have the wooden strip removable from the groove in order that it may be replaced, when worn, by the repeated driving of fastenings therein, whereby the life of the post is materially prolonged. In one of the other faces of the post, preferably that opposite the face having the longitudinal groove, there are provided upper and lower transverse open-ended seats or channels 7 and 8, and pairs of 80 openings 9 pierce the post transversely through the backs of the seats and between the stiffening devices embedded in the post. 85

By reference to Fig. 3 of the drawings it will be noted that the seats 7 and 8 are designed to receive the upper and lower horizontal rails 11 and 12 of a wooden fence, suitable fastenings 14 being passed through the rails and the respective openings 9, said fastenings preferably being in the nature of 90 bolts, so as to snugly secure the rails to the post. Any suitable or approved form of pickets are of course connected to the rails. 95

From the foregoing description it will be understood that the present post is complete in itself and may be put upon the market with or without the wooden strip 4 and the fastenings 14, as these elements may be individually supplied by the purchaser of the posts whenever it is desired to erect the fence. As 100 the body of the post is formed entirely of molded material, it is fireproof and capable of withstanding the effects of the weather, the only destructible portion being the wooden strip, which may be conveniently renewed whenever required. Moreover, the 105 post is adapted for the support of both

wooden and wire fencing without requiring any specially-prepared fencing or fastenings therefor, and it will be observed that the driving of the fastenings 5 into the strip 4 will spread the latter to prevent its removal until the fastenings are withdrawn.

Having thus described the invention, what is claimed is—

A fence-post comprising a body portion having a longitudinal groove therein opening through its front face and having transverse vertically-spaced seats in its rear face, said seats opening through the side faces of the

post, strengthening devices embodied in the post and a fibrous strip engaged in the groove, said seats being arranged for the reception of fence portions therein, said posts having passages formed therethrough communicating with the seats.

In testimony whereof I affix my signature 20 in presence of two witnesses.

DANIEL C. PETRIE.
